PROCESS OF FORMING WELT SHOES

George E. Musebeck, Danville, Ill., assignor to
Musebeck Shoe Company, Danville, Ill., a cor-
poration

Application November 14, 1940, Serial No. 365,594

1 Claim. (Cl. 12—142)

This invention relates to a process of forming a welt shoe.

In orthopedic shoes and in any type of shoe, it is important that the inner surface of the insole retain as long as possible the shape of the last on which the shoe is made. This is particularly true in the case of orthopedic shoes, in the manufacture of which the lasts are carefully shaped to provide particular orthopedic results. The shank stiffeners commonly used in modern shoes are provided with corrugations to give the necessary combination of lightness and strength. Such irregularly surfaced stiffeners placed immediately beneath an insole provide a very faulty surface for supporting the insole since there is a tendency for the insole to collapse into the corrugations of the stiffener and into the spaces left at either side of the stiffener between the insole and the outsole. The effect of repeated applications of the body weight especially on an insole moistened by perspiration and supported on such a faulty surface is to cause a failure of the insole which eventually destroys the original correspondence between the weight bearing surface of the insole and the last.

Even where corrugations in the shank stiffeners are not used, the shape of the shank stiffener seldom conforms exactly to the shape of the last so that the shoes when worn for some time assume the shape of the stiffener rather than the shape of the last. The lack of correspondence between the shank stiffener shapes and lasts is due to the fact that approximately 160 different sizes and widths of lasts are required for a complete line of women's shoes alone, whereas commercial production methods dictate the use of only four or five shapes and sizes of shank stiffener.

The present invention has for its principal object a shoe construction in which the insole is rigidly supported in conformity to the original lasted contour irrespective of corrugations in the shank stiffener, irrespective of differences between the shape of the stiffener and that of the last and independent of cavities normally occurring between the outsole and the insole at the edges of the stiffener. This result is accomplished by embedding the stiffener in a plastic material adapted to harden, as distinguished from the usual resilient ground cork fillers often used in Goodyear welt shoes with or without shank stiffeners. The hardened filler provides a smooth surface rigidly supporting the insole in its original curvature as determined by the last. This is particularly important in the region of the heel 55

seat where a roughened inner surface due to collapse of the insole is most apt to occur and is most uncomfortable.

Other objects and features of the invention and 5 the full nature thereof will be apparent from the following detailed specifications and the attached drawing in which a preferred form of the invention is specifically described in detail:

Fig. 1 is a bottom view of a shoe in process 10 of construction in accordance with a preferred form of the invention. Fig. 2 is a similar view at a further point in the process of manufacture. Fig. 3 is a sectional view of a completed shoe taken on a line corresponding to line 3—3 of Fig. 2.

In Figs. 1 and 2 there is shown an insole 10 to which there has been secured the usual welt 11 and upper 12. In the heel portion the edges of the upper have been folded about the insole 20 and secured thereto in the usual manner. With the shoe in this stage of construction and still on the last, a quantity of a plastic filling material adapted to harden is placed on the insole in the area 13 indicated by stippling. The material 25 preferably employed is sawdust mixed with an adhesive such as the pyroxylin cement used in other steps in shoe making and known as "compo". This material when hardened provides a rigid structure similar in strength and 30 rigidity to solid wood. Preferably a layer one-eighth to three-sixteenths of an inch in thickness is used.

While the filler is still in a plastic condition, a shank stiffener 14, which may be of any common 35 form, is pressed into the material with sufficient force so that corrugations and other irregularities in the surface of the stiffener are filled with the plastic material. The stiffener may be secured by tacks 15 in the usual manner.

40 The plastic material is then permitted to harden and for this purpose heat may be applied if desired. In some cases another layer of plastic material is then applied outside of the shank stiffener and is properly shaped to conform to 45 the desired upper surface of the outsole. In certain cases where metatarsal arch support is particularly desired, extra thickness of the filler is applied outside the shank stiffener in the metatarsal region.

50 The outsole 16 is then applied to the shoe in the usual manner after the last application of the plastic material has been permitted to harden. In the resulting construction the irregularities of the upper surface of the shank stiffener 14 are filled by the hardened filling material 17

(Fig. 3) which rigidly supports the insole 10 in a position determined by the original shape of the last and not by the shape of the shank stiffener. The spaces 18 between the insole around the edges of the shank stiffener are also filled with the rigid supporting material so that there is no tendency for the insole to collapse into such spaces. This is particularly important in the heel seat where a considerable gap is usually present at the point 19 between the shank stiffener and the inturned edges of the upper 12.

The invention has been described in one of its preferred forms, the details of which may be varied by those skilled in the art without departing from the scope of the appended claim.

The invention claimed is:

The process of forming a rigid shoe shank in

a shoe, comprising the steps of applying a filling of sawdust bound with pyroxylin shoemaker's cement to the heel seat and shank of the bottom of the insole while on the last and with the filling extending forward at least to the break line of the shoe, pressing a corrugated stiffener of less length and breadth than said filling layer part way into said plastic filling while said filling is still sufficiently soft to fill the corrugations in said stiffener and to cover the ends and edges of said stiffener, and allowing said material to harden, whereby said filling conforms to the shape of the shoe shank and rigidly retains and supports said stiffener therewith irrespective of irregularities in the shape of said shank stiffener.
